UNITED STATES PATENT OFFICE.

HARRY T. SHEARER, OF WAYNESBORO, PENNSYLVANIA, ASSIGNOR TO LANDIS TOOL COMPANY, OF WAYNESBORO, PENNSYLVANIA, A CORPORATION.

GRINDING-MACHINE.

1,087,072.

Specification of Letters Patent.

Patented Feb. 10, 1914.

Application filed July 10, 1912. Serial No. 708,734.

To all whom it may concern:

Be it known that I, HARRY T. SHEARER, a citizen of the United States, residing at Waynesboro, Franklin county, and State of Pennsylvania, have invented and discovered certain new and useful Improvements in Grinding-Machines, of which the following is a specification.

My said invention relates to grinding machines and particularly to the mechanism for traversing the grinding wheel across the carriage, or to and from the work, its object being to provide such a mechanism which may be quickly and easily operated from a convenient point on the outside of the machine, and one by which said wheel may be rapidly moved to and from its operative position by power taken from the power-shaft of the machine.

20 A further object is to provide such a traversing mechanism which may be readily applied to any machine, it being located upon the outside of the machine casing so that practically no change in the machine structure is required in its application.

With these and other objects in view said invention as illustrated, comprises a shaft operated by a pulley from the belt which drives the grinding wheel, said shaft having mounted thereon a conical friction wheel adapted to engage either one of a pair of friction disks mounted upon a sleeve keyed to the shaft which controls the travel of the carriage which carries the grinding wheel.

35 This mechanism is controlled by suitable levers within convenient reach of the operator.

Modifications in details may be made without departing from my invention which will 40 be more clearly defined in the claims.

Referring to the accompanying drawings, which are made a part hereof and on which similar reference characters indicate similar parts, Figure 1 is a side elevation of the grinding wheel carriage with my improved reversing mechanism applied thereto, Fig. 2 a sectional view looking in the direction of the arrow from the dotted line 2—2 in Fig. 1, and, Fig. 3 a detail section on the dotted line 3—3 in Fig. 2.

In said drawings the portions marked A represent the grinding wheel, B the grinding wheel base, C the grinding wheel carriage, and D the grinding wheel driving belt.

55 The grinding wheel A is mounted upon

the usual spindle a, which carries a pulley a¹ around which passes the belt D. This belt passes over an idler pulley b and down around the driving drum (not shown) of the grinding machine and up over a second idler pulley b¹ and thence around a tensioning pulley b² and back over the pulley a¹ upon the grinding wheel spindle a. This is the usual method of driving the grinding wheel and is illustrated and described as a means of operating the improved reversing mechanism.

The grinding wheel base B is mounted to slide transversely on carriage C, as usual and has a bracket 1 secured thereto. This bracket has an extended arm 2 in which is journaled one end of a short shaft 3. Upon this shaft is mounted a pulley 4 in such position as to contact and press downwardly upon the belt D so that a movement of this belt will transfer power to the said pulley 4. The opposite end of the shaft 3 is journaled at 5 in a cylindrical casing 6 mounted upon an upright shaft 7, journaled in the base B. The inner end of the shaft 3 has a conical friction wheel 8 mounted thereon adapted to contact with either of a pair of friction disks 9 and 10 carried by a sleeve 11 which is splined to the shaft 7. The disks 9 and 10 are adapted to be brought into a driving engagement with the friction wheel 8, the direction of rotation of the shaft 7 being governed by which of said disks is brought into such contact. The movement of the disks 9 and 10 is accomplished by means of an arm 12 whose yoked ends 13 engage a groove 14 formed in one end of sleeve 11. Said arm 12 is pivoted upon a shaft 15 having bearings in the casing 6 and the bracket 2, and upon the outer end of this shaft is rigidly secured an arm 16, the outer end of which is bifurcated to receive the end 17 of a push-rod 18 to form a hinge connection between said arm and push-rod for operating the reversing mechanism. The rod 18 normally holds the sleeve 11 in a central position with disks 9 and 10 equi-distant upon either side of the friction wheel 8, said position being sustained by means of a spring 20 interposed between one side of 105 a support 21, and a collar 22 secured to said rod 18. The outer end of this rod has a handle 23 for convenience in operation.

The shaft 7 upon which the sliding sleeve 11 is mounted extends downwardly through 110

the base B and has a worm 24 formed thereon which meshes with a worm gear 25 threaded upon a shaft 26 located within the carriage C and immediately below the base B. Said shaft 26 is threaded throughout a portion of its length, said threaded portion passing through a threaded perforation in worm gear 25 and an elongated hub 27 thereon. Said hub 27 is mounted in a bearing 28 in an arm depending from base B the gear 25 resting against one end of said bearing and a collar 35 on the outer end of hub 27 against the other end, thus coupling said base to wheel 25 to travel therewith, so that upon rotation of the shaft 26 motion is imparted to the base B in a direction in line with said shaft 26. Shaft 26 is mounted in a bearing 28 formed upon the carriage C and upon the extreme end of this shaft is mounted a beveled gear 29 which engages a beveled pinion 30 mounted upon a shaft 31, forming a part of the grinding machine mechanism.

The operation is as follows: Power is transmitted to the shaft 3 through the belt D and the pulley 4 causing the rotation of the conical friction wheel 8. When it is desired to move the grinding wheel A in a direction toward the work, the rod 18 is operated in the direction to cause disk 9 to engage the wheel 8, which rotates the shaft 7 and through the worm 24 and worm gear 25, operates the threaded shaft 26 and causes said gear 25 to travel along said shaft in a forward direction. When it is desired to reverse the direction of travel of the grinding wheel the rod 18 is operated in an opposite direction causing the disk 10 to engage the friction cone 8 which results in a reverse movement of the direction of travel of the wheel 25.

Having thus fully described my said invention what I claim as new and desire to secure by Letters Patent is:

1. A grinding wheel feed mechanism for grinding machines comprising a screw-shaft secured to and extending transversely of the carriage, a nut embodying a gear and connected to move with the slider, a shaft journaled on said slider and geared to said nut, a friction gear on said shaft, a power shaft, a friction gear on said power shaft, and means for throwing said friction gears into driving contact on either side, whereby said slider may be operated in either direction from said power shaft, substantially as set forth.

2. A grinding wheel feed mechanism for grinding machines comprising a screw-shaft mounted upon and extending transversely of the carriage, a part adapted to travel on said screw-shaft carried by the slider, a shaft journaled in said slider and geared to said part for traveling the same on said screw-shaft, a double-faced friction gear mounted to slide on said shaft, a power

shaft, a friction gear on said power shaft adapted to mesh with either face of said double-faced gear, and means for sliding said double-faced gear to engage either face thereof with said gear on the power shaft, substantially as set forth. 70

3. A grinding wheel feed mechanism for grinding machines comprising a screw-shaft mounted transversely of the carriage, a part with which said screw-shaft engages carried by the slider, a worm-gear formed on said part, a worm-shaft journaled in said slider and engaging with said gear, a power shaft, gearing connecting said power shaft with said worm-shaft for driving said worm-shaft in either direction, and means for operating said gears into and out of engagement for driving in either direction, substantially as set forth. 75 80

4. In a grinding machine, means for moving the grinding wheel toward and from the work comprising a gear part embodying a nut extending transversely of and mounted to move with the carriage, a screw engaging the nut of said gear part, a gear part on the slider engaging with the other gear part, means for driving said gear part on the slider, and means for reversing its motion, substantially as set forth. 85

5. A grinding machine provided with means for moving the grinding wheel toward and from the work comprising a carriage, a slider, a screw-shaft on the carriage, a screw-threaded part on said screw-shaft engaging with the slider to travel therewith, gearing for driving said part, means for reversing the motion of said gear, and means for throwing said gear into or out of engagement, substantially as set forth. 95 100

6. In a grinding machine, the combination, of the grinding wheel carriage, a slider thereon, a grinding wheel on said slider, and means for traversing said slider across said carriage comprising inter-engaging gear parts one on said carriage and the other on said slider, a power shaft, gearing for connecting said power shaft with said gear parts, and means for throwing said gearing in and out of operative connection, substantially as set forth. 105 110 115

7. In a grinding machine, the combination, of the grinding wheel carriage, a slider thereon, a grinding wheel on said slider, and means for traversing said slider across said carriage comprising a gear part on the slider engaging therewith, a power shaft, gearing for connecting said power shaft to said gear part on the slider, means for normally holding said gearing out of engagement, means for throwing said gearing into engagement, and means for reversing the movement of said gear, substantially as set forth. 120 125

8. In a grinding machine, means for moving the grinding wheel toward and from 130

the work comprising a screw-shaft on the carriage, a nut part on said screw-shaft and connected to move with the slider, a worm-wheel on said nut part, a worm-shaft journaled in the slider and engaging the worm wheel on the nut part, a sleeve splined to slide a limited distance on said worm-shaft and carrying a friction gear with two engaging faces spaced apart, a shifting lever connected to said sleeve for operating it, means for holding it in a normal position, a power shaft, and a friction gear on said

power shaft interposed between the friction faces on said sleeve midway thereof and normally out of engagement therewith, substantially as set forth. 15

In witness whereof, I have hereunto set my hand and seal at Waynesboro, Pennsylvania this seventeenth day of June, A. D. nineteen hundred and twelve.
